United States Patent Office

Des. 196,483
Patented Oct. 8, 1963

196,483

HAIR DRYER BONNET OR SIMILAR ARTICLE

Sally Victor, New York, N.Y., assignor to General
Electric Company, a corporation of New York

Filed May 6, 1963, Ser. No. 74,756

Term of patent 14 years

(Cl. D3—13)

FIG. 1

Des. 196,483

FIG. 3

FIG. 1 is a perspective view of a hair dryer bonnet embodying my new design;

FIG. 2 is a top plan view thereof; and
FIG. 3 is a side elevational view thereof.

I claim:

The ornamental design for a hair dryer bonnet or similar article, substantially as shown.
